SCREW DRIVER

Thomas L. Rhodes, Council Bluffs, Iowa

Application February 11, 1952, Serial No. 18,462

Term of patent 7 years

(Cl. D93—4)

To all whom it may concern:

Be it known that I, Thomas L. Rhodes, a citizen of the United States, residing at Council Bluffs, in the county of Pottawattamie and State of Iowa, have invented a new, original, and ornamental Design for a Screw Driver, of which the following is a specification, reference being had to the accompanying drawing, forming part thereof.

Figure 1 is a perspective view of a screw driver, showing my new design;

Figure 2 is a perspective view thereof with the screw driver blade in a reversed position;

Figure 3 is a sectional view, taken substantially in the plane of the line 3—3 in Figure 1, and

Figure 4 is a sectional view, taken substantially in the plane of the line 4—4 in Figure 2.

I claim:

The ornamental design for a screw driver, as shown.

THOMAS L. RHODES.
